UNITED STATES PATENT OFFICE.

DORSEY M. STOCKDALE, OF ELLENBORO, WEST VIRGINIA.

REEL.

1,350,946.

Specification of Letters Patent. Patented Aug. 24, 1920.

Application filed April 29, 1919. Serial No. 293,379.

To all whom it may concern:

Be it known that I, DORSEY M. STOCKDALE, a citizen of the United States, residing at Ellenboro, in the county of Ritchie and State of West Virginia, have invented new and useful Improvements in Reels, of which the following is a specification.

This invention relates to a novel construction of reel for wire and the like and the 10 principal object of the invention is to provide means for easily and quickly securing a roll of wire to the reel with means for winding or unwinding the wire therefrom.

Another object of the invention is to provide indicating means for indicating the 15 length of wire removed from or wound upon the reel.

Still another object of the invention is to provide means for breaking the reel when 20 desired.

The invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying 30 drawings wherein like characters denote like or corresponding parts throughout the several views, and in which:—

Figure 1 is a plan view of the device;

Fig. 2 is a like view with the cover 35 removed;

Fig. 3 is a plan view of the rear face of the lid showing the indicating mechanism;

Fig. 4 is a longitudinal section through 40 the device;

Fig. 5 is a section on line 5—5 of Fig. 4.

In these views 1 indicates the case for enclosing the reel and 2 indicates the cover thereof. As will be seen, the case is of cylindrical form but is provided with a flat 45 portion 3. The lid is also provided with a flat portion 4 which is hinged to the edge of the portion 3. The lid is locked in closed position by the latch 5. A spindle 6 is centrally arranged on the bottom of the

50 case and projects upwardly as shown. This spindle rotatably supports a sleeve or hub 7 which is provided with screw threads at its upper part. This sleeve is held on the spindle by the bolt 8. Arms 9 radiate from 55 said sleeve, said arms forming spokes and

support the circular rack 10. Rollers 11 are arranged around the bottom of the case with which the under face of the rack engages. The teeth of the rack are engaged by the toothed wheel 12 which is secured to 60 a shaft 13 which passes through a journal carried by the flat part 3 of the case and the outer end of said shaft is provided with a handle 14. In this way when the handle is actuated the reel formed by the rack, the 65 spokes and the hub will be caused to revolve. The wheel 12 is inclosed in a recess formed by a depending strip 15 having its upper portion secured to the inner wall of the case and its lower portion curved inwardly to 70 provide the recess. Slotted upright members 16 have guide ways formed at their lower ends which engage the upper surface of the spokes. Toggle levers 17 connect these upright members with the hub and 75 with a sleeve 18 having its interior screw-threaded for engaging the screw threads on said hub. The lower end of the sleeve 18 is provided with a groove 19 and a collar 20 fixed in said groove. One of the links 80 of each toggle lever has its upper end pivoted to said collar and its other end pivoted to the lower part of one of the upright members. The other link of said lever has its upper end provided with a pin which 85 engages the slot in the upright member and its lower end is pivoted to the lower end of the hub. It will thus be seen that by screwing the sleeve 18 downwardly or upwardly on the hub the upright members will 90 be moved away from or toward said hub. In this way the upright members may be moved inwardly so that a coil of wire may be placed around the uprights and then by screwing the sleeve 18 downwardly the uprights will be expanded so as to grip the 95 coil of wire to prevent movement of the coil on said uprights. In order to facilitate the rotation of the sleeve 18 the same is provided with a handle 21 and a hook 22 is 100 connected with said handle by a spring 23. This hook is adapted to engage one of the toggle levers so as to prevent rotation of the sleeve 18.

A brake is provided for the reel and this 105 brake consists of a screw threaded plug 24 passing through a screw threaded opening 25 in the lower part of the case and carrying a spring plunger 26 for engaging an inclined surface 27 on the annular rack. This 110

screw plug is provided with a handle 28 and with a lock nut 29 for holding it in braking position.

- The lid of the case is provided with a downwardly projecting bracket 30 which carries a guide roller 31 for the wire and the lid is also provided with a horizontal guiding tube 32 which is secured to its under face and is provided with enlarged ends.
- 5 10 The inner end is located adjacent the guide roller 31, when the top is closed, and its outer end registers with an opening in the top edge of the case so that the wire may pass therefrom.
- 15 A frame 33 is secured to the under face of the lid and this frame supports a train of gearing 34. One wheel 35 of this train is provided with a grooved periphery and is located adjacent the inner end of the outlet 20 tube 32 so that the wire passing to said tube will be engaged by said groove. A second grooved wheel 36 is carried by a swinging arm 37 and this wheel 36 is moved toward and away from said wheel 35 by a screw 25 threaded rod 38 which is connected with the journal of said wheel 36 and engages the nut carried by the lid. This rod is provided with a handle 39 and with a lock nut 40. When the peripheries of the wheels 35 and 30 36 are in engagement with each other the wire will be gripped between them so that the passage of the wire will cause said wheels to rotate and this rotation will be communicated to a dial 41 which has its 35 rack 42 in engagement with the last wheel of the train. This dial is provided with suitable indicia to indicate the length of the wire passing to or from the device. The lid is provided with an opening 43 through 40 which the dial may be read. The dial is rotatably supported by means of the rollers 44.

It will thus be seen that the coil of wire may be easily and quickly clamped to the

reel or the end of the wire to be wound on 45 the reel can be secured to said reel. The wire can be easily wound upon or unwound from the wheel and whenever desired, the brake may be manipulated to lock the reel against movement. The length of the wire 50 being removed or wound upon the wheel can easily be read from the dial.

It is thought from the foregoing description that the advantages and novel features of my invention will be readily apparent. 55

I desire it to be understood that I may make changes in the construction and in the combination and arrangement of the several parts, provided that such changes fall within the scope of the appended claims. 60

What I claim is:—

1. A reel of the class described comprising a case, a cover therefor, a spindle therein, a hub rotatably mounted on the spindle and having a screwthreaded portion, spokes 65 secured to said hub, slotted upright members slidably engaging with said spokes, a sleeve interiorly screw-threaded and engaging the screw-threaded part of the hub, a collar rotatably carried by said sleeve, toggle levers connecting the upright members with said collar and with said hub.

2. A reel of the class described comprising a case, a spindle carried thereby, a hub rotatably mounted on the spindle and having a screw-threaded portion, a sleeve interiorly screw-threaded and engaging said screw-threaded portion, a collar rotatably carried by said sleeve, spokes secured to said hub, upright members slidably engaging 70 said spokes, toggle levers connecting said upright members with the collar and hub and means for connecting said sleeve with said toggle levers to prevent vertical movement of the sleeve. 75

85 In testimony whereof I affix my signature.

DORSEY M. STOCKDALE.
